UNITED STATES PATENT OFFICE.

CLIFFORD H. McGLOSSON, OF WASHINGTON, DISTRICT OF COLUMBIA.

DESIGN FOR A OUIJA-BOARD.

•6,449.

Specification for Design.

Patented Oct. 26, 1920.

Application filed May 26, 1920. Serial No. 384,471. Term of patent 14 years.

To all whom it may concern:

Be it known that I, CLIFFORD H. McGLOSSON, a citizen of the United States, residing at 4115 Illinois Avenue N. W., in the city of Washington, District of Columbia, have invented a new, original, and ornamental Design for Ouija-Boards, of which the following is a specification, reference being had

to the accompanying drawing, forming part thereof.

The figure is a plan view of a ouija board, showing my new design.

I claim:

The ornamental design for a ouija board, as shown.

CLIFFORD H. McGLOSSON.
